Attorney

UNITED STATES PATENT OFFICE.

HARRY NIELSEN, OF NEW YORK, N. Y.

FISHERMAN'S GLOVE.

1,243,622.

Specification of Letters Patent. Patented Oct. 16, 1917.

Application filed April 19, 1916. Serial No. 92,202.

To all whom it may concern:

Be it known that I, HARRY NIELSEN, a citizen of the United States, residing at New York, in the county of New York and State of New York, have invented new and useful Improvements in Fishermen's Gloves, of which the following is a specification.

This invention is an improved device for use in handling freshly caught fish.

One of the objects of the invention is to provide a glove or similar device, which may be readily placed upon the hand, the same being provided with metallic members having points or serrations adapted to engage the body of a freshly caught fish, to prevent the same from slipping out of the hand. A further object is to provide a glove of the character referred to, with metallic members that are shaped to secure effective results, and which may be readily and firmly attached to the glove.

The invention will be hereinafter fully set forth and particularly pointed out in the claims.

In the accompanying drawing:—

Figure 1 is a perspective view of a glove constructed in accordance with the invention. Fig. 2 is an enlarged plan view illustrating one of the metallic engaging devices. Fig. 3 is a transverse sectional view thereof, illustrating the method of attaching the same to the glove. Fig. 4 is a similar view taken at right angles to Fig. 3.

Referring to the drawing, 10 designates a hand covering, which may be of any desired form or style, a glove being shown for illustrative purposes, the same being provided with the usual finger portions 11, and thumb portion 12, the body of the glove being open at one side as indicated at 13, a suitable strap 14, and buckle 15, serving to secure the glove around the wrist of the wearer.

Located contiguous to the outer ends of the finger portions 11 and the thumb portion 12, inside of the hand, are metallic disks 16, which may be of any desired shape, but preferably star shape in plan view, as illustrated in the drawings, the edges of said disks being outturned, and provided with serrations 17, suitably shaped to slightly enter the flesh of a fish. Said disks are somewhat dished so as to provide a concave back face. The disks are attached removably to the fabric forming the glove, by means of staples 18, the arms of said staples

being passed through suitable spaced apart slots in the bases of the disks, and after passing through the fabric 19, and through corresponding openings in a slightly dished 60 clamping plate 20, said arms are turned over or clenched to retain the parts in position. In order to reinforce the glove to prevent the disks from tearing out, it is preferred to insert reinforcing members 21, of the 65 same material as the glove, between the bases of the disks 16 and the glove fabric. In order to prevent discomfort to the wearer, lining pieces 22 are attached to the glove fabric in position to extend over the clamping 70 plates and staples.

In operation, the glove is placed upon the hand, and the disks 16 are so positioned that the wearer may readily grasp a freshly caught fish in such a manner that the serrations will prevent the fish from slipping out of the hand. By slightly dishing the disks, the ends of the fingers fit thereinto so as to obtain an effective bearing, thereby insuring the grasp of the fish without material relative movement of the fingers and the disks. By employing the staples 18, the disks may be readily secured in position, and should they become damaged, may be easily removed and replaced, with little or no trouble. 85

Having thus explained the nature of my invention and described an operative manner of constructing and using the same, although without attempting to set forth all of the forms in which it may be made, or 90 all of the forms of its use, what I claim is:—

1. A fisherman's glove comprising a hand covering having finger portions and a thumb portion, metallic disks located contiguous 95 to the outer ends of said finger portions and said thumb portions, said disks having out-turned serrated edges and spaced apart slots, and staples passed through the slots of said disks and the body of the hand covering, 100 said staples having their ends bent over to removably retain the disks in position.

2. A fisherman's glove comprising a hand covering having finger portions and a thumb portion, metallic disks located contiguous 105 to the outer ends of said finger portions and said thumb portion, said disks having out-turned serrated edges and spaced apart slots, clamping plates opposite said disks and located within the glove, said plates having 110 openings corresponding to said slots, and staples passed through the slots of said

disks and the openings of said clamping plates and having their ends bent over against said clamping plates to removably retain the disks in position.

- 5 3. A fisherman's glove comprising a hand covering provided with metallic disks having outturned serrated edges, reinforcing members interposed between the respective disks and the hand covering, staples passed through said disks, said reinforcing portions, and the body of the hand covering, said staples having their ends clenched inside of the hand covering, and lining pieces covering the clenched ends of the staples.
- 10 15 4. A fisherman's glove comprising a hand covering provided with metallic disks hav-

ing outturned serrated edges, said disks being dished to provide concaved back faces, staples passed through said disks and extending through to the interior of said hand covering, and lining plates shaped to conform to said disks, the ends of said staples being clenched against the inner faces of said plates.

In testimony whereof I have hereunto set 25
my hand in presence of two subscribing
witnesses.

HARRY NIELSEN.
